UNITED STATES PATENT OFFICE.

MICHAEL G. BURNETT, OF WATERTOWN, MASSACHUSETTS, ASSIGNOR OF FIFTY-ONE
ONE-HUNDREDTHS TO MICHAEL BURKE, OF MARLBORO, MASSACHUSETTS.

ARITHMETICAL CALCULATOR.

1,222,731.

Specification of Letters Patent. Patented Apr. 17, 1917.

Application filed October 30, 1914. Serial No. 869,480.

To all whom it may concern:

Be it known that I, MICHAEL G. BURNETT, a citizen of the United States, residing at Watertown, county of Middlesex, State of 5 Massachusetts, have invented an Improvement in Arithmetical Calculators, of which the following description, in connection with the accompanying drawing, is a specification, like characters on the drawing representing like parts.

This invention relates to an improved mechanical calculator which functions accurately and rapidly to ascertain the arithmetical result for a given multiplicand and 10 multiplier.

The object of this invention is to provide mechanical means for quickly determining the correct number of dollars and cents resulting from the multiplication of a given 15 number of hours by a given rate of wage per hour.

Another object is to provide an arithmetical calculator in which provision is made for a large number of unit rates of wage and 20 for a large number of hour units entailing a proportionately large number of resultant amounts.

As these mechanical calculators are employed periodically it is highly desirable 25 that they should be in such form that they may, when not in active use, occupy a space of small compass. Another object is, therefore, to construct a calculator which is small and compact without impairment of efficiency, accuracy, legibility of characters, or 30 loss of rapidity or facility of manipulation.

A further object is to obtain such a calculator in which only the result desired is 35 presented to view—a decided advantage over the former instruments and one that insures accuracy and rapidity in the attainment of the correct result.

In order to afford an understanding of the invention, a selected embodiment of the same 40 has been illustrated in the accompanying drawings and will now be described.

Figure 1 is a perspective view of the arithmetical calculator and shows the foldable standard;

50 Fig. 2 is a front elevation partially broken away and showing the endless character bearing element;

Fig. 3 is a sectional view on the line 3—3

of Fig. 4; but with the cylinders, fabric and idler removed in order to show the shutter mechanism;

Fig. 4 is a sectional view on the line 4—4, Fig. 3;

Fig. 5 is a section of a modified form of shutter and mechanism therefor;

Fig. 6 is a perspective of the V-shaped bar spring employed in the modified shutter mechanism.

The calculator in this selected embodiment has a casing 1, preferably of sheet metal or 65 other light durable material. The front face of the casing is cut away and a rectangular opening therein provided which extends transversely nearly across the casing. The numeral plate 2 is affixed above and adjacent the top edge of the opening and has delineated thereon, in any suitable manner, characters 3 which in the form shown represent varying amounts of wage per hour. The extreme left column is shown with an 70 abbreviation for the word "hours." The face plate 4 covers the lower portion of the opening and is secured to the casing by the screws 5. The cross-bar 6 is screwed to the casing 1 and is positioned immediately behind the opening in the front face thereof. The cross-bar 6 has a transverse slot 7, extending throughout its length, in which the slide 8 is adapted to travel. The helical spring 9, one end of which is attached to the 75 side of the casing 1 and the other to the slide 8, normally holds the slide to the left limit of its travel.

A window 10, consisting of a long plano-convex lens, extends transversely the opening and is secured to the top of the cross-bar 6 and to the upper edge of the opening in the casing 1. It thus presents a glass surface with magnifying properties through which any characters, passed beneath the 85 "hours" and wage rate characters, may be 90 the more easily read.

The shutters 11 are vertically slidably positioned in front of the casing opening and in their normal position cover the window. 100 A shoulder 12 outwardly projects at the upper end of each shutter and functions as a means for depressing the same. The lower end 13 of each shutter is inwardly bent and enters within the casing through the opening and has secured thereto the lower end of 105

the helical spring 14, the upper end of which is attached to the cross-bar 6. The tension of each of the springs 14 operates to hold the respective shutters 11 in elevated position. 5 A slot 15 is cut in each shutter, providing a series of cam surfaces and detents for the studs 16 secured to the slide 8. When a shutter is depressed the stud 16 rides up the cam surface provided in the shutter slot and 10 thereby moves the slide to the right against the tension of the spring 9 until the lower end 13 of the shutter impinges on the top edge of the casing opening. The stud 16 has then reached the horizontal recess or detent 15 17 of the slot and the tension of the slide spring 9 draws the stud 16 within the recess and locks the shutter in this depressed position against the tension of the shutter spring 14. The portion of the window 10 covered 20 by the particular shutter is then exposed and a clear view is had therethrough. Upon the depression of another shutter, its particular stud functioning in a similar manner, the slide 8 is again drawn to the right 25 and the stud of the former shutter leaves the recess 17 of the former shutter and permits the tension of its spring 14 to elevate the shutter into normal position. The same cycle of operations being completed in the 30 second shutter, another portion of the window 10 is exposed and the former portion is again covered. The shutter mechanism thus automatically operates to close one shutter while another is opened and permits the exposure of but a single portion at a time. 35

The character-bearing fabric 18 is suitably mounted to pass beneath the window 10. The fabric is sub-divided into vertical columns corresponding in width to that of 40 the individual shutters 11. These columns are further apportioned into horizontal rows, and correspond in vertical dimension to the length of the opening made by the lowering of a shutter from its normal position. In the rectangles 19, created thereby, are delineated characters representing, in vertical sequence, amounts of money involving successive hour-wage rate increments. The fabric 18 bears on its extreme left 45 column characters representing the time element—numbers from one upward. This column is adapted to pass before the window 10 immediately beneath the abbreviation for the word "hours" on the numeral plate 2. 50 The fabric 18 is formed of a suitable flexible material and may be mounted and actuated in any suitable manner so as to cause the successive rectangles 19 to pass before and adjacent the window 10. In this selected 55 embodiment, the fabric is adapted to be actuated by the cylinders 20 and 21, revolvably mounted in the casing 1. Perforations 60 22 are provided in the fabric, one series near each edge, and are adapted to engage the teeth 23 of the cylinders 20 and 21. These

cylinders are revolvably mounted in the casing and their shafts 24 and 25 have secured on one end knurled nuts 26 and 27, respectively, by which means the cylinders are rotated as desired. The idler 28, journaled in 70 adjustable brackets 29 secured to the side of the casing 1, serve the double function of retaining the fabric away from the front of the casing and of taking up any slack therein. The tension of the idler on the 75 fabric is increased or diminished by the positioning of the brackets by means of the screw-threaded stud mountings. A gear 30 is affixed to the shaft 25 of the lower cylinder and is revolvable therewith. A detent 31 80 is secured to the side of the casing and its roller stop 32 is adapted to be normally held between the teeth of the gear 30 by the tension of the helical spring 33. As the teeth on the periphery of the gear 30 correspond 85 to the teeth on the cylinders, the detent acts as an impositive lock or detent and functions to accurately and definitely position the cylinder and hence the fabric at any desired point. 90

The arithmetical calculator is supported in operative position by means of the standard 34 apertured near both ends to receive the shaft 24 of the upper cylinder. The standard is adapted to be folded, when the calculator is not in use, along the sides and bottom of the casing and, when in operative position, is secured against movement by any suitable means,—in the form shown, by a leaf spring affixed to each casing side and 100 bearing against an arm of the standard.

The operation of the improved device is simple, rapid and the results are legible and certain. To avoid confusion and possible mistakes, it is highly desirable that several 105 sums be not presented to view when the result of a single arithmetical computation is desired. This is effectuated in this improved construction by means of the shutters. Each of the vertical columns of arithmetical results has a shutter corresponding thereto which, when in depressed position, permits the disclosure of a single rectangle of the table bearing fabric. The scale, transversely affixed to the casing above and 115 adjacent the opening, bears thereon a series of numerals which, in this embodiment, represents different rates of wage per hour in fractions of one dollar. The fabric, as shown, bears in its extreme left column a 120 progressive series of whole numbers from one upward which represents, as indicated on the scale thereabove, the time element—number of hours. To determine the amount due for work or labor, for example as shown 125 in Fig. 1, for 10 hours, when the wage earned is at the rate of \$.25 per hour, one rotates the cylinders which carry the fabric before the opening, stopping when the figure "10" appears under the "Hrs." heading on the scale. 130

The shutter beneath the ".25" rate on the scale is then depressed when there is disclosed the arithmetical result desired. Further, each rectangle of the fabric bears thereon three decimal fractions, representing, respectively, the amounts due for $\frac{1}{4}$, $\frac{1}{2}$, $\frac{3}{4}$ hours at the specified rate per hour designated by the adjacent scale. This result having been noted, and it being desired, for 10 example, to ascertain the amount due for a similar period of time at a wage rate of \$.10 per hour, the shutter under this rate on the scale is depressed, as shown in Fig. 2, which causes the former shutter to rise to normal 15 closed position, and the result desired is solely presented to view.

In Fig. 5 there is illustrated another form of shutter mechanism and means actuated by the depression of one of the shutters for releasing any and all of the remaining shutters which may be in depressed position. This mechanism, as shown, comprises a V-shaped bar 35 extending longitudinally the casing and having a free edge 36 adapted to engage 20 a shoulder 37 of the shutter 11, the shoulder 37 being at the end of the cam surface 38. In this form of the device, the casing may be offset as at 39 to form a stop for the shutter 11 in its raised position and the shutter 25 may be provided with an inwardly extending flange 40, projecting through the casing so that the same may be normally sustained in raised position by a spring 41 attached to said shutter and to the inner side of the 30 casing. It would be obvious that upon the depression of the shutter, the surface 38 will cause the portion 36 of the V-shaped bar to yield sufficiently to release any other shutter which may be secured in depressed position 35 thereby. When a depressed shutter is released it will be drawn upwardly by its spring 41 until the shoulder 37 strikes against the flange portion 39 of the casing. The V-shaped bar 35 is preferably made of spring 40 steel stock. Portions of the bend at the V may be cut through as at 42 in Fig. 6 to decrease the spring action of the free edge thereof if, in rigid steel stock, the spring action is too great when the shutter being 45 depressed and the depressed shutter are distant the length of the bar. A piece of rigid steel stock 43, in this modified construction, is preferably affixed transversely the free edge 36 of the bar 35. This reinforcement 50 effectuates the substantially uniform transmission, throughout the edge 36 of the bar, of the force of the cam surface 38 of a shutter upon a corresponding portion of the bar edge.

60 The shutter may be formed of a piece of sheet metal, the ends being flanged in reverse direction to provide a hand piece for the top and a stop for the bottom of the shutter. The vertical edges of the shutters, when 65 made of thin sheet metal, may be inwardly

bent to form broader vertical bearing edges for each other.

This is a simpler form of construction which may be more cheaply manufactured and it is to be understood that the claims 70 hereto annexed are intended to cover broadly this construction as well as the form illustrated in the remaining figures.

Having fully described my invention what I claim as new and desire to secure by Letters Patent is:

1. In an arithmetical calculator, a casing having an opening therein, a movable element in said casing having a scale and having arithmetical results delineated thereon, a scale on said casing adjacent said opening, said scales coöperating to indicate an arithmetical result, a plurality of shutters in said casing adapted to cover said arithmetical results, means for retaining each shutter 80 normally in closed position and means actuated by the opening of one shutter to cause all other shutters to be closed.

2. In an arithmetical calculator, a casing having an opening therein, a movable element in said casing having a scale and having arithmetical results delineated thereon, a scale on said casing adjacent said opening, said scales coöperating to indicate an arithmetical result, a plurality of shutters in said 90 casing for covering said arithmetical results, a plurality of springs in said casing adapted each normally to retain a shutter in closed position, and means actuated by the opening of one shutter to cause all other shutters to 100 be closed.

3. In an arithmetical calculator, a casing having an opening therein, a movable element in said casing having a scale and having arithmetical results delineated thereon, a scale on said casing adjacent said opening, said scales coöperating to indicate an arithmetical result, a plurality of shutters in said casing for covering said arithmetical results, means for retaining each shutter in normal 105 closed position, a spring controlled cross-bar in said casing, a plurality of studs on said cross-bar, a cam surface in each shutter adapted each to engage one of said studs whereby when one shutter is opened all 110 other shutters will be automatically closed.

4. An arithmetical calculator, including a casing having an opening therein, a plurality of vertically slideable shutters adapted normally to close said opening, means for normally retaining said shutters in closed position, a cam surface and a detent in each shutter, a bar in said casing adapted to traverse said casing, means tending to hold said bar to one side of said casing, a plurality of studs on said bar, said studs each being adapted to engage one of said shutter cam surfaces and detents whereby when one shutter is depressed said detent retains the same in depressed open position and said 125

bar automatically effectuates the release of all shutters and the return of the same to normal closed position.

5. An arithmetical calculator, including a casing having an opening therein, a plurality of vertically slideable shutters adapted normally to close said opening, means for normally retaining said shutters in closed position, means for retaining a shutter in 10 depressed open position and for effectuating the release and return to normal closed position of all other shutters, comprising a bar in said casing adapted to traverse said casing, a spring secured to said bar and to said casing whereby one end of said bar is normally held adjacent the casing side, a cam surface and a detent in each of said shutters formed by a slot and recess therein, a plurality of studs on said bar, one opposite each slot and adapted to engage said cam surface and detent whereby when a shutter is depressed its stud will engage the cam surface, transversely actuate the bar which functions to release any depressed 15 shutter, and said stud will enter said recess and detain the depressed shutter in such position.

20 6. In an arithmetical calculator a casing having an opening therein, a movable element in said casing having a scale and having arithmetical results delineated thereon, a 25

scale on said casing adjacent said opening, said scales coöperating to indicate a single arithmetical result, a plurality of shutters in 30 said casing adapted to cover said arithmetical results, and spring actuated means operable when one shutter is opened to cause automatically the remaining shutters to close.

7. An arithmetical calculator including a 40 casing having an opening therein, a plurality of vertically slideable shutters adapted normally to close said opening, a lower inwardly turned flange on each shutter, a 45 spring secured to said flange and to a cross bar in said casing whereby said shutters are normally held in upper closed position, an upper outwardly turned flange on each shutter whereby said shutters may be depressed to open position, and means adapted automatically to release a shutter held in depressed position upon the depressing of any other shutter, whereby when one shutter is depressed all others are automatically raised 50 to closed position.

55 In testimony whereof, I have signed my name to this specification, in the presence of two subscribing witnesses.

MICHAEL G. BURNETT.
